UNITED STATES PATENT OFFICE.

JOHN B. FRANKE, OF FORT WAYNE, INDIANA, ASSIGNOR TO PERFECTION BISCUIT COMPANY, OF FORT WAYNE, INDIANA, A CORPORATION OF INDIANA.

DISPLAY RACK.

Application filed November 19, 1923. Serial No. 675,653.

My present invention relates to display racks for crackers and like commodities and has for a principal object the provision of a permanent rack built up of units arranged 5 to receive fiber cracker caddies, or like inexpensive shipping containers and being provided with display covers individualized to the caddies and giving the visual impression of a plurality of metal cracker cans disposed 10 in the display rack.

Another object of the invention is the provision of a display rack of this character adapted to receive caddies of different height and to hold them in position for effective dis- 15 play of the contents.

It is also an object of the invention to provide a novel mounting for the display covers which facilitates their use under practical conditions of service and whereby they may 20 be caused to disappear between the different units of the rack and thus be out of the way when they are in open position.

A further object is the provision of a display rack which may be of sectional construction and which may thus be extended to desired capacity, in accordance with local 25 conditions.

Numerous other objects and advantages of the invention will be apparent as it is better 30 understood from the following description, which, taken in connection with the accompanying drawings, discloses a preferred embodiment thereof.

Referring to the drawings, 35 Figure 1 is a front elevation, partially broken away, of a display rack in which my invention is embodied, the same being shown as of sectional construction;

Fig. 2 is a side elevation thereof;

Fig. 3 is an enlarged detail section, taken substantially on the line 3—3 in Fig. 1;

Fig. 4 is a top plan view of the part of the rack shown in Fig. 1; and

Fig. 5 is an enlarged detail plan view of 45 one of the lids, or display covers, and a portion of the top of one of the units of the rack, certain parts being broken away for convenience in illustration.

The rack shown in said drawings, for purposes of illustration comprises front uprights 21 arranged in spaced relationship and rear uprights 22, of angle-iron formation, a top member 23 secured to the tops of said uprights and display units formed of metal receptacles 24 permanently secured to said

uprights one above the other and preferably arranged in inclined position. Said receptacles, or containers, are secured to the uprights 21 and 22 by means of bolts 25 and 26 which extend through the uprights and the metal walls of the containers, washers 27 being preferably employed between the uprights 21 and said container walls to space the latter a sufficient distance inwardly to permit the movement of display covers 28 to and 60 from closed position, as will hereinafter appear. Said containers, as shown, are each of approximately the size of two tin cracker cans, though it will be understood that they might be of greater width, if desired, so as to 65 be of the size of three or more such cans. It will be obvious that the height of the rack may also be varied by substituting uprights of different height, in accordance with the 70 number of display units which it is desired to 75 have supported thereby.

I also provide means for extending the rack laterally so that it may be considered to be of sectional construction. The manner in which this is done will be apparent from 80 an inspection of Fig. 1, in which a second tier of container units 24 is disposed adjacent the rack section formed by two each of the uprights 21 and 22 spaced apart at such distance as to receive one tier of said container 85 units 24 therebetween. Said second tier of container units is supported by the uprights 21 and 22 at one side of the first section and by similar uprights correspondingly spaced therefrom, the end wall of the containers being secured to said uprights in the manner previously described. The top member 23 may be of such length as to cover a single 90 rack section, or a plurality of sections, being shown in Figs. 1 and 4 as of the latter length. 95

The adjacent uprights 21 are connected at the bottom by a bracing rod 29, which, if desired, may be extended through the uprights of adjacent sections to bind the structure together.

Within each container unit 24, there is 100 provided space for two cracker caddies or shipping cartons which may be supported at the front of the container by means of supporting strips 31, which may be soldered or otherwise secured to the top and bottom walls of said container and are spaced apart a suitable distance to permit the insertion of a caddy body therebetween with the usual flaps on said body folded over said strips and 105 110

extending downwardly within the container. Viewing Fig. 1, it will be noted that one of said strips is positioned adjacent the outside wall of the container and the other at such distance inwardly therefrom as to provide for the reception of the caddy therebetween. Channels 32 are formed midway between the side walls of the container and form short wall sections 33 for a purpose which will 10 hereinafter appear.

The display covers 28 are provided with peripheral flanges 34 adapted to frictionally engage the walls of the container, including the short wall sections 33, and the rear flange 15 is cut away, as indicated at 35. A hinge member, or pintle, 36 is disposed on the inner side of said rear flange and has its ends disposed within pockets 37 and 38 arranged on opposite sides of the cut-out portions 35.

20 Steel guide members 39 are provided upon the top wall of the container and extend through the cut-outs 35, above the pintle rod 36. Said guide members are riveted at one end to the top wall of the container, as indicated at 41 and at the opposite end are turned inwardly, as indicated at 42 and secured to the inner side of said wall by soldering, or in any preferred manner. Said guides are bent upwardly at 43 beyond the point of attachment 41, to space them away from the container wall, and it will be obvious that when the display cover 28 is raised, it may slide back upon said container wall to the extent permitted by said guides 39. Said 30 guides 39 are bent upwardly at 43 beyond the point of attachment 41, to space them away from the container wall, and it will be obvious that when the display cover 28 is raised, it may slide back upon said container wall to the extent permitted by said guides 39. This 35 preferably is a sufficient distance to permit the cover to substantially disappear between the container units, as indicated at the bottom of Fig. 3. It is, of course, apparent that said guides 39 may be secured in place in any desired manner and that the cover may be secured within said guides in any way that manufacturing operations and considerations of economy may render expedient. The pintle rod 36 is provided with a handle 40 part 44, whereby it may be readily withdrawn when it is desired to remove the cover.

A glass, or other transparent panel 45 is secured within a central opening 46 in said display covers by means of supporting clips 50 47 of Z-form, which are attached by soldering or otherwise to the underside of the covers, there being in the present instance four of these clips, one disposed on each side of the opening 46.

55 The top edges of the container walls are beaded inwardly, as indicated at 48, and it will be apparent that, to all intents and purposes, each container unit comprises two tin cracker cans of the ordinary variety.

60 The rack, as above described, provides display fronts of pleasing and substantial appearance and the contents of the caddies not only are effectively displayed, but are protected from moisture and from damage which might result from their being stored

merely in said caddies which are made of fiber and afford meager protection and poor display facilities. The structure is permanent and provides a less expensive means of display than is afforded by the purchase of 70 crackers in the relatively expensive tin display cans which are often employed instead of the cheaper caddy in order that the dealer may have a means of displaying his wares.

It is thought that the invention and many of its attendant advantages will be understood from the foregoing description, and it will be apparent that various changes may be made in the form, construction and arrangement of the parts without departing 80 from the spirit and scope of the invention, or sacrificing all of its material advantages, the form hereinbefore described being merely a preferred embodiment thereof.

I claim:

1. A display rack comprising, uprights, a container supported by said uprights and adapted to receive a shipping carton having flexible side flaps, said container having an open mouth and provided with bars spaced apart from two parallel sides of said mouth adapted to have the flaps of the carton bent backwardly and inserted between said bars and the sides of the carton for holding said carton in position.

2. A display rack, comprising uprights, a container secured to said uprights and adapted to receive a plurality of shipping cartons, said container being formed with intermediate wall sections forming with the main walls a plurality of cover-receiving sections corresponding to the number of cartons adapted to be held, and a display cover adapted to frictionally engage each of said sections.

3. A display rack, comprising uprights, a container permanently secured to said uprights and adapted to receive a plurality of shipping cartons, said container being formed with intermediate wall sections forming with the main walls a plurality of cover-receiving sections corresponding to the number of cartons adapted to be held, a display cover adapted to frictionally engage each of said sections, and guides upon the top of said container for retaining said covers and permitting them to slide back upon the container wall when open.

4. A display rack, comprising, a supporting member, a container mounted on said supporting member, said container being adapted to receive a shipping carton having flaps adapted to form a closure and to be folded back against the sides of the carton, means within said container adapted to engage the folded flaps of said container for supporting the carton, and a display cover for said container and carton.

5. A display rack, comprising a supporting means, a shipping carton holder sup-

ported thereby, said holder having side members adapted to hold the shipping carton in display position on said support, said holder having means spaced from said side members for receiving between said means and said side members portions of a carton to support said carton in display position, and a cover carried by said holder, adapted to close the open mouth of the carton.

10 6. A display rack, comprising a supporting member, a carton holder supported thereby and adapted to receive a shipping carton formed with flexible side flaps, said carton holder having an open mouth and provided with means spaced away from two parallel sides of said holder, at the mouth thereof, to permit the flaps of the carton to be inserted between said spaced means and parallel sides for holding said carton in position.

20 7. A display rack, comprising, a supporting member, a carton holder thereon adapted to receive a shipping carton, said holder having an open mouth and means on said holder for supporting the carton and holding it in position on said holder by means of the usual flexible side flaps of the carton, and a closing member adapted to close the mouth of said carton holder and said carton.

25 8. A display rack, comprising, a supporting member, a carton holder supported thereby and having an open mouth, a display carton, and means engaging the usual flexible

flaps on said carton, positioning said carton in said holder with the mouth of the carton registering on the mouth of the holder, and a transparent cover shiftably mounted and adapted to close the mouth of said holder and said carton, whereby the contents of said carton may be viewed through said cover.

35 9. A display rack, comprising a supporting member, a carton holder supported thereby, the holder having an open mouth, a display carton, a transparent cover shiftably mounted on the carton holder adapted to close the mouth of the holder and the contained carton, and means within the holder to maintain the mouth of the carton presented to and immediately under the mouth of the holder, said means being adjustable for

40

45

50

55

60

10. A display rack, comprising a supporting member, a carton holder supported thereby adapted to receive a plurality of display cartons, display cartons therein, a plurality of transparent covers slidably hinged to a wall of the container, each cover adapted to provide an individual sealed closure for the cartons, and means within the container to maintain the mouth of the carton presented to and immediately under the mouth of the container, said means being adjustable for cartons of different depth.

JOHN B. FRANKE.
